FURNACE CONSTRUCTION

Oscar F. Gettlieb, Lake Bluff, Ill., assignor to
 Oakes Products Corporation, North Chicago,
 Ill., a corporation of Michigan

Application July 16, 1934, Serial No. 735,405

10 Claims. (Cl. 266—5)

This invention relates to a furnace construction, suitable for heat treating, welding and brazing operations, having a heating chamber provided with dies for holding the material being heated.

More specifically this invention relates to a batch type brazing or welding furnace provided with a stationary bottom die for receiving metal articles to be welded or brazed and a vertically movable top die cooperating with said bottom die to clamp or hold the metal being treated to prevent the same from becoming warped or buckled and to aid the welding or brazing operations.

It is an object of this invention to provide a furnace construction with a heating chamber therein equipped with a pair of dies for holding metal articles during the heating operation.

Another object of this invention is to provide a metallurgical furnace having mechanically operated metal holding dies in the heating chamber thereof.

A specific object of this invention is to provide a furnace for welding or brazing metal articles having a stationary bottom die for receiving said metal articles and a vertically movable top die for holding said articles in proper shape under pressure during the heating operation.

A further object of this invention is to provide a furnace construction with mechanically operated dies mounted in the heating chamber thereof.

Another object of this invention is to provide a furnace structure with a mechanically operated charging door.

Another specific object of this invention is to prepare a welding or brazing furnace construction in which metal articles are held in position during the heat treatment by a pair of mechanically operated and electrically controlled holding dies.

Other and further objects of this invention will be apparent to those skilled in the art from the following description and annexed sheets of drawings which form a part of this specification.

On the drawings:

Figure 1 is an end elevational view of a preferred form of furnace construction according to this invention with the charging door removed and with parts in vertical cross-section.

Figure 2 is a central cross-sectional view taken substantially along the line II—II of Figure 1.

Figure 3 is a broken end elevational view showing the charging door construction of the furnace.

Figure 4 is an enlarged cross-sectional view of the holding dies taken substantially along the line IV—IV of Figure 1.

Figure 5 is an enlarged cross-sectional view of the holding dies taken substantially along the line V—V of Figure 2.

Figure 6 is a diagrammatic wiring diagram of the electrical control means for the holding dies and charging door.

As shown on the drawings:

In Figures 1, 2, and 3 the reference numeral 10 indicates generally the frame structure for the furnace. Insulating material 11 such as fire bricks or the like is built up in said frame structure 10 to define the top, bottom and sides of 15 a heating chamber 12.

The chamber 12 may be heated by gas through a plurality of ports such as 13 shown in Figure 2. Obviously the chamber may also be heated by electrical means or by any other means without departing from the principle of this invention.

As shown in Figures 1 and 2 a bottom die or mold 14 is supported in the heating chamber 12 in spaced relation from the walls thereof on a 25 plurality of vertical rods 15 extending through the bottom of the furnace. The rods 15 are slidable in tubes 16 mounted in the bottom of the furnace and are pivotally secured at their ends to the arms 17 of shock absorbing and leveling supports 18 mounted below the furnace in the frame structure 10.

Each support 18 includes the arm 17 which is keyed to a shaft 19 rotatably mounted in the support 18. A second arm 20 is also keyed to the 35 shaft 19 and is slotted near the end thereof to receive the pin 21 of a boss 22 slidable over a horizontal rod 23. Springs 24 are held under compression between the bosses 22 and adjusting nuts 25 in screw thread relation with the ends of 40 the rod 23. Locking nuts 26 may also be provided to set the nuts 25 in adjusted relation.

This supporting structure provides a mounting for the bottom die 14 which is readily adjusted to level the die and which permits downward movement of the die toward the furnace floor when top pressure on the die exceeds the desired limit. The die is thus cushioned against sudden overload and is readily adjusted in alignment.

A plurality of ears or lugs 27 are integrally secured around the peripheral edges of the bottom die 14. Each ear 27 carries a pin 28 extending vertically upward therefrom.

A top die 30 is superimposed over the bot-

tom die 14 and has a plurality of apertured ears or lugs 31 for receiving the pin 28 therethrough.

The top die 30 is suspended from a plurality of rods 32 extending through the roof of the furnace in slideable relation to tubes 33 which are secured in the furnace roof. The rods 32 are also slideable through bosses 34 having flanges 35 resting on the top of the furnace for sealing the apertures in which the tubes 33 are mounted.

The top ends of the rods 32 are coupled by means of couplings 36 to the lower ends of shafts 37 which are slideable through bosses 38. The bosses 38 are pivotally connected at 39 (Figure 1) to a link arm 40. The link arm 40, at the other end, is pivoted at 41 to a vertical link arm 42 which is pivotally connected at 43 to the frame 10 of the furnace.

The bosses 38 are connected by a horizontal shaft 44. The middle of the shaft 44 is pivotally connected at 45 to the piston rod 46 of an air cylinder 47 which is suspended from the frame structure 10 by a pivot 48. The top portions of the shafts 37 are slideable through bosses 49 which are swivelled at 50 to the frame structure 10.

The pivots and swivel connections permit swinging the air cylinder and attendant lifting mechanism away from the tops of the rods 32 so that these rods may be readily inserted in position through the furnace roof. It is obvious, of course, that the lifting mechanism may be rigidly mounted above the furnace without departing from the principle of the invention.

From the above description of the air cylinder mechanism it is obvious that a piston 51 in the air cylinder 47 may be raised by compressed air to lift the top die 30 in spaced relation from the bottom die 14. Likewise compressed air may be used to force the piston 51 downward to maintain the dies 14 and 30 in pressure relation.

As shown in Figures 2 and 3 the furnace is provided with a charging door 60 which is vertically slideable in tracks or guides 61 and 62 carried by the frame structure 10 in front of the furnace. A yoke 63 is secured to the top of the charging door and is provided at the center thereof with an eye member 64 which member receives the end of a cable or flexible metal band 65.

Horizontal channel beams 66 are mounted to the tops of the tracks or guide members 61 and 62. A shaft 67 extends between the channel members 66 to form an axle for a lever 68 having an arcuate end 69 thereon. The arcuate portion 69 is grooved in the center thereof as indicated at 70 to form a seat for the cable 65.

The other end of the lever 68 is pivoted to the piston rod 71 of an air cylinder 72. The air cylinder 72 is pivoted to the track member 62 at 73.

The above described structure provides mechanical means for raising and lowering the charging door 60. It is obvious that a reciprocation of the piston rod 71 of the air cylinder 72 will result in a tilting of the lever 68 about the axle 67 to raise and lower the arcuate portion 69, thereby wrapping and unwrapping the cable 65 in the groove 70.

Figures 4 and 5 illustrate a specific form of dies 14 and 30 that are used for holding the inner shell 80 and the outer shell 81 of a preferred form of sheet metal evaporator unit for refrigerators. The shells 80 and 81 are to be welded together along their inner contacting surfaces during the heat treating operation in the furnace. It is ob-

vious, of course, that any shape or form of dies 14 and 30 may be used in place of the dies shown in Figures 4 and 5 without departing from the principle of this invention.

The top die 30 is preferably formed in two sections 30a and 30b respectively which are bolted together by means of bolts such as 82.

Each section 30a and 30b in the top die 30 is provided with an integral boss member 83 for receiving therein a lifting rod 32 described above. 10

The bottom die 14 shown in Figures 4 and 5 is formed in three sections 14a, 14b, and 14c respectively. The end sections 14a and 14c are joined to the central section 14b by means of rivets or bolts indicated at 84. The end sections 14a and 14c of the lower dies 14 are equipped with integral couplings 85 for receiving therein the ends of the supports 15. Likewise the central portion 14b of the lower die 14 is provided with an integral coupling 86 for receiving the center support 15. 20

The lower die 14 is thus coupled to the supports 15 in the couplings 85 and 86 provided therein while the upper die 30 is coupled to the lifting rods 32 by means of the couplings 83. Any other securing means, of course, may be used without departing from the principle of this invention.

It should be noted that the dies 14 and 30 contact the evaporator shells 80 and 81 only opposite interior surfaces that are to be welded. These surfaces are thus pressed into contact while the 30 stamped depressions in the shells are not affected by the pressure between the dies.

In the wiring diagram shown in Figure 6, the reference numerals 90 and 91 indicate the main power lines forming a source of electric current 35 of standard voltage. These power lines 90 and 91 are connected through a double pole switch 92 to lead-in wires 93 and 94 which are joined to a standard delayed action switch unit 96 and a relay switch 97.

The air cylinder 47 for raising and lowering the top die 30 in the furnace is supplied with compressed air through pipe lines 98 and 99. The pipe lines 98 and 99 are coupled at their other ends with a valve 100 having a manually operated 45 control lever 101 pivoted above the valve at 101a.

Air or other compressed fluid is supplied from a suitable source (not shown) through a throttling valve 102 into the control valve 100. An exhaust line 103 is connected with the control valve 100 50 for permitting the escape of air from the cylinder 47.

The air cylinder 72 for controlling the operation of the charging door 60 is likewise connected through pipe lines 104 and 105 to a control valve 106. The valve 106 is supplied with compressed air or other fluid from a source not shown through a throttle valve 107. The fluid may be exhausted through an exhaust pipe 108. A manually controlled lever 109 is pivoted at 109a above the control valve 106.

Solenoids 110 and 111 having armatures 110a and 111a are positioned respectively adjacent to the valves 100 and 106. The armatures 110a and 111a are pivotally connected with the valve control levers 101 and 109 respectively.

When the control levers 101 and 109 of the valves 100 and 106 are depressed, air is allowed to pass through the throttle valves 102 and 107 70 respectively into the pipe lines 99 and 104 respectively for lowering the piston in air cylinder 47 to drop the die 30 on the stationary die 14 and for raising the piston in air cylinder 72 to the lower door 60. At the same time, however, 75

the armatures 110a and 111a are also raised by the control levers 101 and 109. The delayed action switch 96 has been previously set to operate for a predetermined period of time before the contacting point 112 therein closes the circuit between the wires 113 and 114. When the circuit between the wires 113 and 114 is closed, current from the wire 93 travels through the wire 114 to energize the relay switch 97 thereby closing the same. When the relay switch 97 is closed the solenoids 110 and 111 are energized to depress their respective armatures 110a and 111a thereby throwing the valves 100 and 106 so that the operating fluid from the throttle valves 102 and 107 will be exhausted from the pipes 99 and 104 and directed into the pipes 98 and 105. In this manner the piston in air cylinder 47 is automatically raised and the die 30 lifted vertically in the furnace while the charging door is automatically opened by forcing the piston in the cylinder 72 downward. In this manner the article to be welded or otherwise heat treated between the dies 14 and 30 is maintained under pressure in the dies for an exact predetermined time interval. When the predetermined time interval has elapsed the top die is automatically raised and the charging door is automatically opened to permit removal of the welded or heat treated article.

In order to set the delayed action switch 96 for the next operation a knocker bar 115 is mounted on the under side of the lever 68 from which the furnace door 60 is suspended. The knocker bar 115 comes into contact with the end 116 of a pivoted bar 117 which normally makes contact between wires 118 and 119, to energize the motor in the delayed action switch. When the knocker bar 115 depresses the pivot arm 117, however, contact between the wires 118 and 119 is broken and the motor is de-energized. The contact point 112 of the delayed action mechanism then drops back into the position indicated in dotted lines at 112a for resetting the motor. When the valve control arm 101 is again manually depressed for the next operation the piston rod 71 is raised and the knocker bar 115 is moved out of contact with the pivot arm 117 thereby permitting it to again make contact between the wires 118 and 119 to thereby energize the motor in the delayed action switch for starting the operation described above. It is obvious that other arrangements of relay switches and control valves may be used in place of the specific embodiment shown in the wiring diagram.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. A furnace construction comprising a heating chamber, a die mounted in the central portion of said heating chamber in spaced relation from the walls thereof, a plurality of vertical supports for said die extending through the bottom of said chamber and means for adjusting said supports to control the level of said die.

2. A furnace construction comprising a heating chamber with top, bottom and side walls, said top and bottom walls having apertures extending therethrough, a die in the central portion of said heating chamber in spaced relation from the

walls thereof, a plurality of vertical rods extending through the apertures in the bottom of said heating chamber for supporting said die, means outside of the heating chamber for adjusting the rods to level the die, a top die superimposed over said first mentioned die, a plurality of rods extending through the apertures in the top wall of said heating chamber secured to said top die and means for raising and lowering said rods.

3. A furnace construction comprising a heating chamber having top, bottom and side walls, tubes extending through said top and bottom walls, a bottom die in said heating chamber in spaced relation from the walls thereof, a plurality of rods extending through the tubes in the bottom wall of said heating chamber, means for raising and lowering said rods to level said bottom die, a top die superimposed over said bottom die, a plurality of rods secured to said top die, slidably in the tubes in the top wall, an air lifting apparatus connected with the ends of said rods and means for actuating said lifting apparatus to vertically move said top die relative to said bottom die.

4. In a furnace, a central heating chamber having top, bottom and side walls, a stationary die in said chamber in spaced relation from the walls thereof, a plurality of vertical supports for said die extending through the bottom wall of said heating chamber, means below the bottom wall for adjusting said supports to level the die and resilient means for transmitting the adjusting movement to the supports whereby said die is both resiliently and adjustably supported in the furnace.

5. A furnace comprising a frame structure, heat resistant walls carried by said frame defining a heating chamber, hollow tubes extending through the top and bottom walls, rods slidable in said tubes, a pair of cooperating dies mounted on said rods in said chamber and means to slide said rods in the tubes to level one of said dies and to move the other of said dies in spaced relation therefrom for receiving an article therebetween.

6. In a furnace construction having a die mounted therein on rods which extend through the bottom of the furnace, supporting means for each of said rods below the furnace comprising a horizontal shaft, a horizontal arm keyed to said shaft at one end thereof, a boss on the other end of said arm for receiving said rod, a vertical arm keyed to said shaft, a horizontal rod normal to said shaft, a boss slidable on said rod for engaging said vertical arm and a spring held under compression on said horizontal rod to maintain said arm in vertical position.

7. A furnace comprising, in combination, a heating chamber, a die in said heating chamber, rods secured to said die for holding the same in position in the heating chamber, rotatably mounted shafts below each rod having an arm keyed thereon for receiving the end of a rod, a horizontal rod extending between two adjacent shafts in spaced relation from said shafts, bosses slidable on said rod, a second arm keyed on each of said shafts for engaging one of said bosses, coil springs on the ends of said horizontal rod urged against said bosses and means for varying the compression of said springs to level said die.

8. A furnace construction comprising a heating chamber having a bottom wall, a die in said chamber, a plurality of supports for said die extending through the bottom wall of said heating chamber, arms pivoted to the ends of said supports, rotatable shafts for supporting said arms

in fixed relation thereon, spring means for holding said shafts against rotation and means to adjust said spring means for rotating the shafts individually whereby said die is resiliently supported and adjusted from outside of the heating chamber.

9. A furnace construction comprising a heating chamber having a bottom wall, a die in said chamber, a plurality of supports for said die arranged in spaced pairs and extending through the bottom wall of the heating chamber, rotatably mounted bell cranks arranged in pairs having one arm thereof pivoted to the ends of each pair of supports, rods extending between each pair of bell cranks, bushings slidably mounted on

said rods and secured to the other arms of the bell cranks, coiled springs disposed around the ends of the rods for acting against the bushings thereon and means to adjust the compression of said springs whereby the die is resiliently supported and adjusted from outside of the heating chamber.

10. A furnace construction comprising a heating chamber, a die mounted in the central portion of said heating chamber, a plurality of supports for said die extending through the bottom of said chamber and means outside of said chamber for adjusting said supports to control the level of said die.

OSCAR F. GOTTLIEB. 15
